UNITED STATES PATENT OFFICE.

JOHN H. JEFFRIES, OF INGLEWOOD, CALIFORNIA.

COMBINATION SWITCH-LOCK.

1,189,956.

Specification of Letters Patent.

Patented July 4, 1916.

Application filed September 20, 1915. Serial No. 51,543.

To all whom it may concern:

Be it known that I, JOHN H. JEFFRIES, a citizen of the United States, and a resident of Inglewood, in the county of Los Angeles and State of California, have made an Improvement in Combination Switch-Locks, of which the following is a specification.

My invention relates to improvements in combination locks and switches and particularly for motors for vehicles and boats.

In starting motors it is customary to turn the switch to the battery for preliminary sparking, and then when the motor is running, it is switched to the magneto. It is also desirable at times to lock the parts in such a position that the motor can not be tampered with, or operated by a person other than the owner or an authorized employee, when the owner or driver leaves the vehicle in a public thoroughfare for any purpose and hence the machine can not be stolen or used surreptitiously.

The object of this invention is then primarily to provide a simple arrangement of switch mechanism and locking means which is positive in action, and one in which the parts can be manipulated to cut out the sparking mechanism.

With this and other objects in view my invention consists in certain features of construction, arrangement and combination of parts as will be hereinafter described and pointed out in the claims, reference being had to the drawing in which—

Figure 1 is a face view of the device as applied to the dash of an automobile or motor boat. Fig. 2 is a vertical section of same on line 2—2 of Fig. 1. Fig. 3 is a bottom plan view. Fig. 4 is a vertical section on line 4—4 of Fig. 2. Fig. 5 is a vertical section on line 5—5 of Fig. 2. Fig. 6 is a detail perspective view of the auxiliary switch lever. Fig. 7 is a detail perspective view of the bolt device. Fig. 8 is a perspective view of the tumblers and accessories used in the combination or permutation locking mechanism.

Referring more particularly to Fig. 1, it will be seen that I provide a casing "A" secured to the dash "B" by screws or otherwise, and having the front face A' made as a dial. Within casing is a back plate "C" faced with insulation C' all held to the dash by a screw as shown. A switch "D" of the double-throw type is mounted

to swing on pivot D' forming a binding post to which the conductor "E" is clamped; this double-throw switch comprises the lever D² and the curved knife blade spring arms D⁴ designed to be swung into contact with the contacts D⁴, D⁵ connected at the rear of the insulation with the conductors D⁶, D⁷ running to the battery and magneto respectively. The back plate "C" has an opening 65 through which the binding post passes but not in contact therewith. The back plate "C" also has a hooked arm C² passing through the insulation above the binding post and a slotted arm or stud C³ at its 70 base, the purpose of which will later appear. The casing is divided into two compartments by a partition "F" fitting within the casing and securely fastened to disks therein, said partition having a central elongated slot F' through which a pin G fastened to bar G' projects said pin being secured to the upper end of an auxiliary switch lever G² having a downwardly projecting hook G³ at its upper end, another 80 hook G⁴ near its lower end a slot G⁵ above the lower hook in which may play the pin or lug D⁸ on the front face of the double-throw lever D²; the auxiliary lever passes downwardly through a slit A² in the casing, 85 said slit having an enlarged central portion as at A³. At the extreme lower end of the lever, a handle G⁶ is provided. Projecting forwardly from bar G' is the bolt member G⁸.

A spindle A⁴ projects through the front of the casing and is secured to a spacing ring A⁵; the spindle has a longitudinal groove a⁴ in one face in which fit the teats H² L² O² and Q² in the central openings of 95 disks H, L, O, and Q, shown in Fig. 8; separating these disks are the disk rings R having slots R' and the disk S having a slot S' to register with the notches R' in the rings R. The disks H, I, M and P, having notches 100 H', I', M' and P' while the disks I, J, K, M, N and P have pins I² J² K² M² N² and P², projecting laterally from one face which are designed to engage projections J', K', L', N' and shoulders O' and Q' on the disks J, K, 105 L, O, and Q respectively. On the outer end of the spindle is placed a milled head T for manipulating the tumblers of the lock and a hand or pointer U is secured to the spindle for movement over the graduated front face 110 of the casing, as is well known in this type of combination locks. With auxiliary switch

lever in the position shown in dotted lines in Figs. 2 and 5 to the lock, pull the auxiliary lever back in slit A² to the center enlargement and let it drop, the hook G³ catching on C² and the hook G⁴ dropping into slot in C³; give the knob of the spindle a few turns and the combination is on. To open, turn the knob until notch I' registers with the slot R' in the adjacent ring R; then 10 in an opposite direction until the slot in the next disk M' registers with the before-mentioned slots and so on till all the slots in the disks and rings are in alinement, H' being the last and this being brought about by 15 projections and pins on the several disks contacting; when the slots are all in registry, the auxiliary lever can be raised, freeing the hooks G³ and G⁴ and carrying the bolt G⁸ into the space made by the aligned 20 slots; the lever G² can now be swung to either side and carrying the double-throw lever with it and will contact with either the contact of the battery or magneto depending on which side the auxiliary lever is 25 swung.

The disk S supports the spindle at the rear and separates the tumblers from contact with the other part of the device. The hooks G³ and G⁴ also prevent lock from being taken from the dash of the vehicle when 30 combination is on as it locks casing to back plate, which is itself fastened to dash by screws from the inside.

I claim:

35 1. A combination switch lock comprising a casing, a double throw switch arm mounted therein, and contact plates over which said arm may be turned, a spindle journaled in the casing, tumblers within the casing and 40 mounted on said spindle, and controlled thereby, an auxiliary switch lever slidably and pivotally mounted in the casing, means for coupling the said auxiliary lever with the throw switch arm, and means pivotally 45 carried by the auxiliary lever for engaging the aforesaid tumblers and operatively coupling the auxiliary lever with the spindle, whereby the throw switch arm may swing into contact with either a battery or 50 magneto circuit.

2. A combination switch lock comprising a casing, a double-throw switch arm mounted therein, contact plates over which the switch arm may be turned, said switch arm 55 having a forwardly projecting pin, an auxiliary switch lever mounted in the casing, said lever having a slot adapted to be engaged by the pin on the throw lever, a spin-

dle rotatably mounted in the casing, tumblers within the casing controlled by said 60 spindle and means for operatively coupling the spindle with the auxiliary arm, whereby the throw lever may be swung into contact with either a battery or magneto circuit.

3. A combination switch lock comprising 65 a casing, a double-throw switch arm mounted therein, contact plates over which the switch arm may be turned, said switch arm having a forwardly projecting pin, an auxiliary switch lever slidably mounted in the 70 casing, and having an elongated slot adapted to receive the forwardly projecting pin on the double-throw switch arm, an arm pivotally suspended from the auxiliary lever, a bolt projecting transversely from 75 said arm, a spindle rotatably mounted in said casing, and slotted tumblers rotatably mounted in the casing and controlled by said spindle, whereby the bolt may be brought into the slots when in register and 80 permit the auxiliary lever to be swung to move the double-throw lever into contact with a battery or magneto circuit.

4. A combination switch lock comprising 85 a casing, a back plate, three posts mounted in said back plate, contact plates connected with two of said posts, a contact lever arm mounted in the casing and adapted to be swung from one contact plate to the other, said arm having a forwardly projecting pin, 90 a back plate having forwardly projecting upper and lower lugs, the upper lug having a hooked end and the lower lug having a slot therethrough, an auxiliary switch lever 95 slidably mounted in the casing having rearwardly projecting hooks adapted to engage the aforesaid upper and lower lugs and provided with an elongated slot to receive the pin on the arm of the throw lever, when in off position, an arm pivotally engaging the 100 auxiliary lever, a bolt projecting forwardly from the lower end of said arm, a spindle rotatably mounted in the casing at the front thereof, rotatable tumblers within the casing controlled by said spindle, said tumblers 105 having slots adapted to be brought into alinement, whereby the bolt may be moved into said slots and permit the auxiliary switch lever to be slid vertically, and swung to the right or left to cause the double-throw lever to contact with the battery or magneto circuit.
